UNITED STATES PATENT OFFICE.

ELMER A. WILSON, OF NILES, OHIO.

METAL STRUCTURE.

1,095,055.

Specification of Letters Patent. Patented Apr. 28, 1914.

Application filed June 24, 1910. Serial No. 568,711.

To all whom it may concern:

Be it known that I, ELMER A. WILSON, a citizen of the United States, residing at Niles, in the county of Trumbull and State 5 of Ohio, have invented certain new and useful Improvements in Metal Structures; and I do hereby declare the following to be a full, clear, and exact description of the invention, such as will enable others skilled in 10 the art to which it appertains to make and use the same.

My invention relates to metal structures similar to metal lathing but adapted for use as the skeleton of plaster partitions.

15 My objects are to economize in the expense of erecting fire proof partitions and to provide a durable metal skeleton or lathing which is capable of receiving and anchoring plaster on both of its sides.

20 Other objects will become apparent from the following description.

The invention consists in the features of construction and combinations of parts hereinafter described and specified in the claims.

25 In the accompanying drawing: Figure 1 is a perspective view of a piece of sheet metal, constructed in accordance with my invention. Fig. 2 is a cross section thereof. Fig. 3 is a front elevation of a modified construction, and Fig. 4 is a cross section of the latter.

35 Referring first to Figs. 1 and 2 of the drawing, 1 designates a piece of sheet metal, 2, 3 and 4 the middle and outside slits of each group of three therein, and 5 and 6 the loops which are drawn out on the opposite surfaces of the structure. It will be noted that a large cavity 7 is formed between each adjacent pair of loops 5 and 6 which is 40 capable of receiving a considerable quantity of plaster and thereby effectively anchors the plaster coatings on both sides to the metal sheet. These two coatings are in reality connected or cemented together by the 45 portions which extend into said cavities so that a partition thus formed is very durable. The metal sheet is strengthened by corrugations 8 extending between and parallel with the rows of loops.

50 As illustrated in Figs. 3 and 4, each loop may have its sides bent inward toward each other, as at 9, so that at the middle portion thereof, said sides are substantially parallel. The edges of said sides are preferably made

irregular, as at 10, to afford better anchor- 55 age for the plaster.

I claim:

1. A structure, of the character described, consisting of a piece of sheet metal having parallel corrugations therein and a row of 60 arched loops extending longitudinally between said corrugations, each row of loops comprising an equal number struck up on each of the opposite faces of the sheet substantially as shown and described and ar- 65 ranged side by side in pairs, the pairs in alternate rows being staggered with respect to those in the other rows.

2. A structure, of the character described, consisting of a piece of sheet metal having 70 parallel corrugations therein and pairs of arched loops struck up on both sides thereof in alignment between said corrugations, each of said loops having its sides bent inward toward each other, all for the purposes speci- 75 fied.

3. A structure, of the character described, consisting of a piece of sheet metal having parallel corrugations therein and a row of 80 arched loops arranged between each pair of said corrugations, each row of loops comprising spaced apart pairs extending longitudinally of said corrugations and arranged end to end, each pair consisting of one loop struck up on each of the opposite faces of 85 the sheets substantially as shown and de- scribed, and the pairs in alternate rows being staggered with respect to those in the other rows.

4. A structure, of the character described, 90 consisting of a sheet of metal formed with a plurality of parallel corrugations and pro- vided with a series of parallel slits arranged in groups of three between each pair of parallel corrugations, the metal between the 95 middle slit and one of the outside slits of each group being drawn outward on one side of said sheet and the metal between said middle slit and the other outside slit being drawn outward on the other side of 100 said sheet forming loops projecting from both surfaces of the structure, each of said loops having its sides bent inward toward each other, all for the purposes specified.

5. A structure, of the character described, 105 consisting of a piece of sheet metal having parallel corrugations therein and rows of arched loops arranged between said corru-

gations, each row of loops comprising spaced apart pairs extending longitudinally of said corrugations and arranged end to end, each pair consisting of one loop struck up on 5 each of the opposite faces of the sheets, and the pairs in alternate rows being staggered with respect to those in the other rows, each of the loops having its sides bent inward

toward each other substantially as and for the purpose specified.

10

In testimony whereof, I affix my signature, in presence of two witnesses.

ELMER A. WILSON.
